UNITED STATES PATENT OFFICE.

PETER GYSBERT THOMAS DE VILLIERS, OF PRETORIA, TRANSVAAL, SOUTH AFRICA,
ASSIGNOR OF ONE-HALF TO ARTHUR ROGERS-JENKINS, OF DURBAN, NATAL,
SOUTH AFRICA.

COIN-ACTUATED SIGNALING APPARATUS.

Application filed December 3, 1920. Serial No. 427,950.

To all whom it may concern:

Be it known that PETER GYSBERT THOMAS DE VILLIERS, a British subject, residing at Department of Posts and Telegraphs, general post office, Pretoria, Transvaal Province, of the Union of South Africa, has invented certain new and useful Improvements in Coin-Actuated Signaling Apparatus, of which the following is a specification.

The present invention has reference to apparatus such as is employed in public telephone call offices, in which a signal actuated by the insertion of a coin is transmitted to a central office to indicate that the necessary payment has been made.

It has especial reference to such apparatus in which the signal is made by means of a reed which is vibrated by the fall of a coin and by such vibration makes and breaks an electric circuit to actuate a signal at the central office.

One of the drawbacks of such apparatus as hitherto used, is that the reed can be caused to vibrate by striking the call box, and thereby giving a false signal.

The present invention is illustrated in the accompanying drawing, in which—

Fig. I shows a coin chute and the reed, and

Fig. II is a horizontal section on A—A Fig. I.

In the drawing, 1 indicates the usual bent coin chute through which the coin passes from the insertion slot to the money box. 2 is the reed having an electric contact piece 3, which, upon the reed being vibrated, makes a trembling connection with the fixed contact 4 and thereby actuates the signal, indicating to the exchange operator that the coin has been inserted. In the present usual construction, said reed projects into the coin path to be struck directly by the coin, and is at all times free, so that jarring of the box can set it in vibration.

According to the present invention, the reed is normally locked, and is unlocked and vibrated by the passage of the coin. For this purpose there is provided a pivoted bell crank 5, 6, one arm 5 of which projects into the coin path 7 in the chute 1. The other

arm 6 normally engages the free end of the reed holding it steady with the contact 3 away from the contact 4. The end 8 of the reed is turned to form a rest for the arm 6, said arm being so weighted with relation to the arm 5 that it falls by gravity into engagement with the end 8. By making the rest 8 higher or lower the position of the arm 5 can be varied, and consequently the time taken by the coin to pass said arm 5.

On the reed immediately above the end 8 is a cross bar 9 which is engaged with and displaced by a roller 10 upon the arm 6 upon said arm being raised.

The operation is that the reed 2 is normally held against vibration by the arm 6 of the lever. Upon a coin falling down the chute 1, it displaces the arm 5 of the lever, and raises the arm 6. Such movement snaps the roller 10 over the cross bar 9 and sets the reed vibrating. When the coin has passed the lever falls back to its normal position, and relocks the reed.

The time during which the reed vibrates is thus definitely determined; and without detriment to the clearness of the signal, this period can be so limited that in a multiple coin box several reeds can be individually vibrated in rapid succession without confusion of their signals.

I claim:

1. In a coin actuated signal apparatus, a coin chute, signal producing means including in part a vibratile reed, means for locking said reed against vibration and means for vibrating it, and means, responsive to the passage of a coin through the chute, for releasing said locking means.

2. In coin actuated signaling apparatus, the combination with a vibratile reed forming part of a signal mechanism, of means to lock and vibrate said reed, said means being actuated by the passage of a coin to unlock the reed and vibrate the same.

3. In coin actuated signaling apparatus, the combination with a coin chute, of a vibratile reed, and a bell crank one arm of which projects into the coin path of the chute, and the other arm of which normally locks the reed, said bell crank being moved

by the passage of a coin through the chute to unlock the reed.

4. In coin actuated signaling apparatus, the combination with a coin chute, of a 5 brittle reed, a bell crank one arm of which projects into the coin path of the chute, and the other arm of which normally locks the

reed, said bell crank being moved by the passage of a coin through the chute to unlock the reed, and co-operating means on the 10 bell crank and the reed whereby such movement vibrates the reed.

In testimony whereof I affix my signature.

PETER GYSBERT THOMAS de VILLIERS.
